UNITED STATES PATENT OFFICE

158,222

PIPE

Oscar Schmidt, Burbank, Calif., assignor of one-third to Jerry Hughes, and one-third to Merry Goldstein, both of Los Angeles, Calif.

Application August 19, 1949, Serial No. 4,610

Term of patent 14 years

(Cl. D85—8)

To all whom it may concern:

Be it known that I, Oscar Schmidt, a citizen of the United States, residing at Burbank, in the county of Los Angeles and State of California, have invented a new, original, and ornamental Design for a Pipe, of which the following is a specification, reference being had to the accompanying drawing, forming part thereof.

In the drawing.

Fig. 1 is a perspective view of a pipe, showing my new design;

Fig. 2 is a bottom plan view, looking in the direction of the arrow 2 of Figure 1;

Fig. 3 is a side elevation, looking in the direction of the arrow 3 of Figure 1; and

Fig. 4 is a front elevation of the pipe, looking in the direction of the arrow 4 of Figure 1.

I claim:

The ornamental design for a pipe, as shown.
OSCAR SCHMIDT.
